UNITED STATES PATENT OFFICE.

EDGAR W. SWANK, OF LIBERTY, MISSOURI.

CASH-BOOK.

1,297,417.

Specification of Letters Patent. Patented Mar. 18, 1919.

Application filed December 2, 1916. Serial No. 134,584.

To all whom it may concern:

Be it known that I, EDGAR W. SWANK, a citizen of the United States, residing at Liberty, in the county of Clay and State of Missouri, have invented certain new and useful Improvements in Cash-Books; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to a cash book, and more particularly to a book of this character for the recording of financial transactions, including receipts from a single source that are intended for distribution under 20 separate classifications or heads; the principal object of the invention being to simplify the entries by providing for a single entry of the name of the payer and a divided entry of the amount paid, whereby the proper 25 amounts may be entered in the specified classes, and whereby the receipts and disbursements are entered in such juxtaposition as to render the auditing and balancing of the accounts convenient and accurate.

30 More particularly, the invention relates to church accounting, and the specific embodiment of the invention is peculiarly adapted thereto for the reason that in such accounting the payments are frequently 35 made in lump sums to be applied to separate expense and mission funds. In the following description of the invention I have specified such use of the book with the understanding, however, that the scope of 40 the invention is not so limited.

In the drawings wherein the preferred form of the book is illustrated,

Figure I is a perspective view of a record book embodying the invention and showing 45 the column for the entry of the name or designation of the payer and payee, and the relation of the separate account columns therewith.

Fig. II is a plan view of a portion of the 50 double entry sheets, with the short sheet in position for entering the receipt in the separate classification columns, or in condition for entering disbursements from the mission fund.

55 Fig. III is a similar view showing the short sheet in open position, *i. e.*, with the

book in condition for entering disbursements from the general fund.

Referring more in detail to the drawings:

1, 2 and 3 designate separate leaves of a 60 book wherein records may be kept in accordance with the invention; the sheet 1 constituting the original entry and a part of the general distribution sheet being ruled to provide a column 4 for the date of the 65 entry, a column 5 for the name of the account, a folio column 6, and a double column 7 comprising a money-received sub-column 8 and a money paid-out sub-column 9; the 70 balance of the page comprising a section 10 embodying columns 11 for entering disbursements under the specified heads.

The sheet 2 comprises on the page 2—A columns 12 similar to the columns 11 of the section 10 of page 1, so that when the sheet 75 is folded back on the sheet 3 it forms a continuation of the page 1 to provide for a sufficient number of specified disbursement columns 11. On the opposite page 2—B of sheet 2, and at the free edge thereof, is a 80 double column 14 having sub-columns 15 and 16 corresponding to the sub-columns 8 and 9 of the columns 7 on page 1; the sheet 2 being of such length that when lying on the sheet 1 the column 14 will lie next to the 85 column 7 of sheet 1, so that when the name of the account is entered in the column 5 of sheet 1 the amount paid in may be separated and part entered in the sub-column 8 of column 7 of page 1 and the balance 90 entered in the sub-column 15 of column 14 of sheet 2.

As indicated in Fig. 1, wherein in the eighth line from the top, we note the entry "Envelope collections" with the entry 95 "\$36.90" in the sub-column 8 of sheet 1 and "\$20.65" in the sub-column 15 of sheet 2, the entry indicating that the envelop collection of January 16th—the date of the entry—was \$57.55 and that the donors indicated that \$36.90 of the amount was to be applied to general expense and \$20.65 to missions.

Page 2—B of sheet 2 differs from page 4 of sheet 1, however, in that the columns to 105 the right of the first entry column of sheet 2 are double-ruled and not only have the headings specifying the general account but also sub-headings specifying "Received" and "Paid", so that both receipts and disbursements may be entered in the specified classification columns of this sheet. The sheet 110

2 is of substantially one-half the length of sheet 1, so that the page comprising sheet 1 and sheet 2 are of substantially the same length as the page comprising sheet 2 and sheet 3; the opposite pages of sheet 2 co-operating with the sheets 1 and 3 according to the position of the sheet 2.

It is apparent that with this book so constructed and ruled, when the receipt items 10 are being entered, the sheet 2 may be folded onto the sheet 1 so that the separate entries may be made without the necessity for two entries of the account designation and with the separate amounts; the account designation being entered on the sheet 1 and the divided amounts on the sheets 1 and 2.

It is further apparent that if the missions account is to be divided that the designated sums may be placed in the proper 20 columns on page 2—B of sheet 2 at the same time the entry on the general expense page is made. When a disbursement is to be entered the name of the payee or the designation 25 of the payment may be entered in column 5 of page 1, and the full amount of the disbursement entered in sub-column 9 of page 1 or sub-column 16 of page 2, and that the same amount may then be entered in the proper disbursement column 11 of page 30 1 or 16 of page 2.

In this way the book may at any time be balanced by footing the sub-columns 8 and 9 of page 1, or an analytical balance secured

by footing all of the columns of pages 1, 2 and 3.

Having thus described my invention, what I claim as new therein, and desire to secure by Letters-Patent, is:

In a church cash book for keeping account of receipts and expenditures, the combination with a primary record page having an expense column, an explanation column, a receipts and expenditures column adjacent to the expense column, and a plurality of disbursement columns continuing therefrom, 40 and a secondary record page having a plurality of disbursement columns thereon, an intermediate fly sheet of relatively lesser width than the said primary and secondary pages and having disbursement columns on 45 one face corresponding to and continuous with those on the primary page when the said sheet is folded to overlie the secondary page, and on its opposite face having a receipts and expenditures column adjacent to its free edge and a plurality of disbursement 50 columns continuing therefrom corresponding with those of the secondary page; the width of the intermediate sheet being such that when overlying the primary page the 55 receipts and expenditures column thereon lies next adjacent to the receipts and expenditures column on the first sheet for the purpose set forth.

In testimony whereof I affix my signature. 60
EDGAR W. SWANK.

Copies of this patent may be obtained for five cents each, by addressing the "Commissioner of Patents, Washington, D. C."
